(No Model.)

O. COLVIN.

CLOTHES POUNDER.

No. 271,602.

Patented Feb. 6, 1883.

UNITED STATES PATENT OFFICE.

ORSON COLVIN, OF SCHOOLCRAFT, MICHIGAN, ASSIGNOR TO WILLIAM T. SMITH AND WILLIAM FANCKBONER, OF SAME PLACE:

CLOTHES-POUNDER.

SPECIFICATION forming part of Letters Patent No. 271,602, dated February 6, 1883.

Application filed June 9, 1882. (No model.)

To all whom it may concern:

Be it known that I, ORSON COLVIN, a citizen of the United States, residing at Schoolcraft, county of Kalamazoo, State of Michigan, have 5 invented a new and useful Clothes-Pounder, of which the following is a specification.

My invention has for its object certain improvements in devices for supporting the pounder in the tub.

10 In the drawings forming a part of this specification, Figure 1 is a side elevation of the device for supporting the pounder, connected with a tub, a portion of said tub being broken away, showing the pounder located 15 therein; Fig. 2, a top view with the pounder and its arm or handle removed from the support, and Fig. 3 a rear view of the pounder-support in Fig. 1.

Bar E supports in a horizontal position the 20 platform a', with which it is pivotally connected at e'. The rear end of this platform a' is supported by an adjustable brace, t, pivotally connected at t', and having its lower end slotted, and secured to the support E by 25 means of set-screw h. By this means the platform a' and its burden may be adjusted to a horizontal plane, whatever may be the varying angle of the side of different tubs with which the pounder-support is connected.

30 Bar E' is provided with hooks f c', catching over each end of the staves of the side of the tub, Fig. 1. The upper hook, f, is provided with a set-screw, n, located in a slot of bar E, Fig. 3, by which means said hook is adjusted vertically. Lever d engages serrations S of bar E, and is connected with hook f by means of pivoted rods n' n'. By this means 35 the hooks f c' are made to firmly grasp the side of the tub by working the lever d up and down, when, by setting the screw n, the pounder-support is firmly held, securely connected with the tub T.

c is a carriage, pivoted to platform a' at P' in a manner to swing laterally. Said carriage c is provided with rollers v v, over which 45 and under flanges m m the arm-extension a of handle B is movably located, thus obviating great friction of parts. Arm-extension a is provided with an upright, P, in a slot of which 50 is pivoted handle B at 7.

D is the pounder-handle, having the upward

slotted extension F', in said slot of which is pivotally connected said handle B at 4.

The platform a' and its carriage may be supported by a standard connecting with its center and independent of the tub, and so arranged that the pounder can be swung from one tub around into another on the opposite side of the standard-support. 55

Any pounder-base desired may be used with the support shown; but a style deemed very practical by me is shown at P. r is a lip or roof over the vertical perforations, which prevents the water from spurting upward.

In the operation the water rises or enters 65 the center space bounded by rim 3 and in the space between the rims 1 and 2, forming a vacuum in the space between rims 2 3. This secures greater ease in operation, more pounding effect on the clothes, greater agitation of 70 the water, with no sloshing and sufficient suction, and the water flows from the space between rims 2 and 3 over rims 2 and 3 into the space of which they form a boundary, as before explained. The carriage e is provided 75 with a hooked flange, m', catching under the curved end of the platform a', to prevent the rear end of the carriage from unduly rising during the operation of pounding the clothes.

Having thus described my invention, what I 80 claim is—

1. A standard provided with the hooks for grasping the side of the tub, the slot in which the upper hook is adjustably located and held by the set-screw, the serrated portion, and the 85 ratchet-lever connected with said adjustable hook by the pivotally-coupled rods, all substantially as set forth.

2. A clothes-pounder support consisting of a standard for connecting with a tub, a platform pivotally connected with its upper end, a brace-arm pivoted to said platform and adjustably connected with the standard, and a carriage pivoted on said platform, provided with the friction-rollers and flanges, forming 90 a way for the extension-arm of the pounder-handle, all substantially as specified and shown. 95

ORSON COLVIN.
